LOUDSPEAKER MOUNTING

Duncan E. Graham, Denver, Colo., assignor of
one-half to John Sovis, Jr., Arvada, Colo.

Application May 31, 1946, Serial No. 673,497

2 Claims. (Cl. 181—31)

1

This invention relates to table-type furniture, and has as a primary object to provide a novel, improved, and pleasing design and construction for a multi-purpose table adapted to operatively house and resonantly temper the output of a radio receiver.

A further object of the invention is to provide a novel and improved combination of a multi-purpose table and a radio receiver.

A further object of the invention is to provide a novel and improved combination of a radio receiver in output-tempered relation with a multi-purpose table.

A further object of the invention is to provide an improved table-type radio receiver mounting arranged to resonantly temper and uniformly distribute the receiver output.

A further object of the invention is to provide an improved resonating sound-box for the tempering and distribution of radio receiver output.

A further object of the invention is to provide an improved construction and arrangement of elements constituting a resonating sound-box for output tempering and distributing association with a radio receiver.

A further object of the invention is to provide an improved multi-purpose table construction incorporating a resonating sound box for the tempering and distribution of radio receiver output.

A further object of the invention is to provide an improved construction and arrangement of elements constituting a combined multi-purpose table and integrally-associated radio receiver output resonating sound-box in the form of a pleasing and useful article of furniture.

With the foregoing and other objects in view, my invention consists in the construction, arrangement, and operative combination of elements hereinafter set forth, pointed out in my claims, and illustrated by the accompanying drawing, in which—

Figure 1 is a side elevation of a specific and preferred embodiment of the invention. Figure 2 is a cross section taken on the indicated line 2—2 of Figure 1. Figure 3 is a vertical section taken substantially on the indicated line 3—3 of Figure 1. Figure 4 is a bottom plan view of the unit assembly shown in the preceding figures.

As represented by the views of the drawings, the preferred embodiment of the novel concept typifies a cocktail, coffee, or similar low table constructed to operatively house a radio receiver in accordance with and to give effect to the principles of the invention, such an article of furniture being particularly well adapted to demonstrate and give full scope to the utilitarian functions and functional advantages of the improved combination.

In the drawings, a hollow, box-like base or

2

table support is shown as a unitary assembly of suitably and rigidly interconnected panels defining a plurality, in this instance three, of like, hollow leg elements 10 symmetrically radiating from a common center in uniform, angular spacing and interiorly communicating with an unobstructed space centrally of the base unit assembly delimited by panels 11 vertically coextensive with and closing between adjacent leg elements. Obviously, the number of leg elements 10 may be varied as desired upwardly from the minimum shown, and said elements, together with the panels 11, may be fabricated from any suitable material and conjoined in any feasible or desired manner effective to produce a rigid and sturdy unit assembly, but considerations of use in association with a radio receiver, as well as of appearance, point the desirability of wood as a material for all of the assembly panels. Lower ends of the elements 10 and panels 11 are worked to a common plane perpendicular to the base unit axis of symmetry whereupon, if desired, the unit may be adapted to rest, but it is deemed more practical and satisfactory to provide each element 10 with a suitably-located, fixedly-associated block 12 depending below the unit lower plane for engagement with and to elevate the unit slightly from a supporting floor or analogous surface. The base unit lower end may be closed, if desired, in which case the blocks 12 may be fixed to the exterior surface of the closing means, but for convenience of access to the base unit interior it is preferred that the said unit lower end be left open and the blocks 12 otherwise mounted, as, for example, by means of stretchers 13 bridging between opposite sides and at the lower end of each element 10 inwardly adjacent the element face.

Upper ends of the base unit assembly panels are worked to a common plane parallel to that of the panel lower ends and in such spacing from the latter as will provide a finished table of the desired height, and a flat, rigid, circular member 14, preferably of wood and of a diameter corresponding with that desired for the finished table, is centered on and fixed to the base unit upper end to preferably project slightly beyond the element 10 outer faces.

Centrally of the member 14 a circular aperture is formed to open through said member to the base unit interior and of a size to accommodate and mount a radio speaker 15, conveniently of cone type, therein secured for direction of its output upwardly and axially of the base unit. The speaker 15 is served by and functions to audibly translate and disseminate the output of a radio receiver unit 16, of conventional type, housed within the upper portion of one of the base unit leg elements 10 and therein removably and replaceably secured in any conveniently

feasible manner. The face of the leg element housing the receiver 16 is apertured, windowed, or otherwise suitably worked, as at 17, for exposure of the received dials, and the receiver controls are extended through the leg element face to receive knobs 18, or equivalent exteriorly-available facilities, whereby said controls may be manipulated for adjustment of the receiver 16.

Overlying the speaker 15 and in upwardly-spaced, concentric parallelism with the member 14, a flat, rigid, imperforate top 19, preferably of the same diameter, thickness, and material as said member 14, is fixed to upper margins of and secured in completing relation with the other elements of the assembly by a plurality, in this instance three, of panel-like struts or spacers 20 fixedly upstanding from and radially of the upper surface of the member 14 in uniformity of angular spacing thereon; said struts 20 preferably corresponding in thickness and material with the member 14 and top 19 and each extending radially of the assembly from the margin of the aperture accommodating the speaker 15 to the registered peripheries of the member 14 and top 19.

Constructed, arranged, and equipped as illustrated and above described, the novel assembly is pleasingly designed for use as a table convenience of sturdy construction, wide adaptability, and smooth, unobstructed top area. Supplementing, and in no way interfering with, use of the assembly as a table, the member 14, top 19, and struts 20 constitute a sound-box in operative association with and to resonantly distribute the output of the speaker 15, so that, the receiver 16 being connected with a suitable source of energy, as by means of a "plug-in" flexible conductor 21, and tuned by means of the control knobs 18, the speaker output impinging centrally of the top 19 under side is deflected to pass radially and outwardly through the space between the member 14 and top 19 with uniform intensity throughout a full circle of delivery, thereby insuring adequate listener reception regardless of listener position relative to the speaker, and at the same time impingement of the speaker output against the top 19 center is productive of vibratory reaction in the rigidly-interconnected sound-box which, when the elements are properly proportioned, qualitatively enhances the speaker output with felicitous resonant effect. Obviously, for best resonant modification of speaker output, the vibratory characteristics of the material forming the member 14, top 19, and struts 20, the thickness of said elements, the diameter of the member 14 and the top 19, and the spacing between said latter elements, are all factors to be correlated with the receiver and speaker output characteristics of a given installation, but experience has established that the structural proportions illustrated in the drawings are productive of a sound-box resonantly satisfactory in association with conventional-type radio equipment when the elements 14, 19, and 20 are formed from a good quality of close-grained wood.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. A resonating sound-box for radio speakers adapted for dual functioning as a table top comprising a flat, circular member formed with a circular, central aperture, supporting means engaging one face of said member about said aperture in non-intersection with the plane of the other member face, a second flat, circular member marginally registered with and spacedly paralleling said first member to close in spaced opposition of its plane control area over the aperture of said first member on the side thereof remote from said supporting means, imperforate panel struts fixedly closing between adjacent faces of said members in uniform angular spacing radially of said aperture between the aperture and member margins, the space between said members and their margins being unobstructed except for said struts, and a speaker supportedly registered with said aperture on the same member side as said supporting means in non-extension through the apertured member for delivery of its output through said aperture against the second member plane central area and to the space between said members.

2. In a resonating sound-box for radio speakers adapted for dual functioning as a table top, a first flat, circular member formed with a circular, central aperture, means for the support of said member engaged with one face thereof about said aperture in non-intersection with the plane of the other member face, a second flat, circular member marginally registered with and spacedly paralleling said first member to close in spaced opposition of its plane central area over the aperture of said first member on the side thereof remote from said supporting means, imperforate panel struts fixedly closing between adjacent faces of said members in uniform angular spacing radially of said aperture between the aperture and member margins, the space between said members and their margins being unobstructed except for said struts, and a speaker supportedly registered with said aperture on the same member side as said supporting means in non-extension through the apertured member for delivery of its output through said aperture against the second member plane central area and to the space between said members.

DUNCAN E. GRAHAM.
